UNITED STATES PATENT OFFICE.

LEWIS B. DOMAN, OF EAST SYRACUSE, NEW YORK, ASSIGNOR TO THE AMPHION PIANO
PLAYER COMPANY, OF SYRACUSE, NEW YORK, A CORPORATION OF NEW YORK.

WIND-INDUCING DEVICE FOR SELF-PLAYING MUSICAL INSTRUMENTS.

1,293,729.

Specification of Letters Patent.

Patented Feb. 11, 1919.

Application filed February 14, 1916. Serial No. 78,175.

To all whom it may concern:

Be it known that I, LEWIS B. DOMAN, a citizen of the United States of America, and resident of East Syracuse, in the county of 5 Onondaga, in the State of New York, have invented new and useful Improvements in Wind - Inducing Devices for Self - Playing Musical Instruments, of which the following, taken in connection with the accompanying drawings, is a full, clear, and exact 10 description.

This invention relates to certain improvements in wind - inducing devices for self-playing musical instruments involving the 15 use of a wind chest, one or more pumping bellows and a driving motor therefor connected and assembled in a relatively small compact space and adapted to be installed as a unit within the case of the instrument for 20 operating the pneumatic sound - producing action, the winding and rewinding rollers for the note sheet and other moving parts of the player which it may be desired to control by air tension produced by the pumping 25 bellows.

In other words, this device constitutes the power plant for the operation and control of practically all of the automatically moving parts of the entire instrument, and by 30 reason of this fact is liable to be more or less noisy in operation, some times to such an extent as to interfere with the musical tones, particularly after the instrument has been in use for a greater or less period of 35 time.

The main object, therefore, of my present invention is to reduce this noise to a minimum or to an inappreciable degree.

Another object is to provide means where- 40 by the motor and pumping bellows together with the wind chest may be easily and quickly installed or removed from the front of the instrument without displacing the rear supports therefor.

45 Other objects and uses relating to specific parts of the apparatus will be brought out in the following description.

In the drawings—

Figure 1 is a front elevation of my im- 50 proved wind-inducing device.

Fig. 2 is a top plan of the same.

Fig. 3 is an enlarged vertical sectional view of the same device taken on line 3—3, Fig. 2, omitting the motor which is shown 55 in dotted lines.

Figs. 4, 5 and 6 are a horizontal sectional view and vertical sectional views taken, respectively, on lines 4—4, 5—5 and 6—6, Fig. 1.

As illustrated, this wind-inducing device 60 comprises a wind chest —1—, a plurality of, in this instance four, pumping bellows —2— arranged in pairs and mounted on opposite sides of the wind chest —1—, an electric motor —3— and suitable means for transmit- 65 ting motion from the motor to the several bellows.

This power - transmitting means prefer- ably consists of a crank shaft —4— jour- 70 naled in suitable brackets or standards —5— which are supported upon the upper edge of the wind chest —1—, as shown more clearly in Fig. 3, the crank arms of the shaft —4— being connected by pitmen —6— to arms —7— on the movable sides of their respec- 75 tive bellows —2— for positively operating the movable sides of the bellows in both directions.

The upper ends of the arms of opposite bellows are connected by coil springs —8— 80 which are placed under sufficient tension to hold the ends of the pitmen —6— firmly against their respective journal bearings on the shaft —4— against lost motion, thereby reducing the liability of rattle or excessive 85 noise from this source.

The shaft —5— extends forwardly and rearwardly and is provided at its front end with a relatively large pulley —9— which is connected by a belt —10— to a relatively 90 small pulley —11— on the corresponding end of the motor —3—, thus permitting the several bellows to be operated with consider- able power through the medium of a rela- 95 tively small motor.

The motor is, of course, driven at high speed and under ordinary conditions of in- 100 stallation within and upon a portion of the instrument case would cause more or less vibration of the various parts of the case, and consequent noise, but in order to over- 105 come this the feet of the motor are secured to a plate —12— of wood or other suitable material, said plate being preferably rec- tangular in top plan and in turn rests upon a non-vibratory pad —13—, preferably of soft or sponge rubber or may be of felt or equivalent substance.

The pad is surrounded and held in place by a marginal frame —14— also of wood 110

or other suitable material, which together with the pad may rest flatwise upon a horizontal shelf —a— forming a part of the lower portion of the instrument case, the 5 pad —13— being of slightly greater surface area than that of the plate —12— so as to support said plate and motor independently of the frame —14—, the latter being secured to the shelf —a— by suitable fastening 10 means, as —15—.

The supporting plate —12— for the motor —3— rests loosely upon the upper surface of the pad —13— and is held against lateral or endwise displacement by a band or strap 15 —16— having one end secured between one side of the frame —14— and shelf —a— at one side of the motor, and its other end passed around the upper side of the motor to the opposite side thereof where it is provided with a loop —17— for receiving a removable retaining member —18—.

This retaining member preferably consists of a round bar extending forwardly and rearwardly through and beyond the opposite edges of the loop —17— and substantially parallel with the axis of the motor, the upper faces of its opposite ends being flattened to form bearings for the heads of suitable fastening means, as screws 30 —19—, which are screwed into the adjacent side of the frame —14—.

The rear end of the strap-retaining bar —18— is bifurcated or slotted to permit it to be placed endwise under the head of the adjacent screw —19— and withdrawn therefrom in securing and releasing the motor-retaining strap or band —16—.

The other screw —19— at the front end of the bar —18— is passed through an opening therein so that in order to remove the motor, it is only necessary to remove the screw —19— on the front end of the retaining bar, whereupon the latter may be withdrawn forwardly from the loop —17—, thus permitting the latter to be drawn to one side to permit the removal of the motor, this operation being reversed in placing the motor upon the pad —13—.

The strap or band —16— is preferably 50 made of canvas or other strong and durable material of approximately the same width as the periphery of the cylindrical periphery of the motor case and may be tightened when necessary by simply tightening the screws 55 —19—, under which conditions the pad —13— will yield slightly, thus reducing constant tension upon the strap to firmly hold the motor in place without liability of transmitting its vibrations to any part of the instrument to such an extent as to produce appreciable noise.

The front and rear edges of the wind chest —1— are pivotally mounted near their lower ends upon adjacent supporting brackets 60 —20— and —21—, which in turn are secured

by screws —22— or other suitable fastening means to the upper surface of the shelf —a—, thus permitting the entire wind chest, together with the bellows mounted thereon to rock laterally toward and from the motor, the object of which is to permit the belt to be tightened or loosened in a manner hereinafter described, and also to permit the entire wind chest and bellows to be rocked downwardly on to the shelf, as 70 shown by dotted lines in Fig. 1, where it may rest while the front bracket —20— is being removed in case it is necessary to take out this portion of the wind-inducing device independently of the motor.

The front bracket —20— is provided with an upward extension —23— having a V-shaped groove —24— in its side opposite the motor for receiving the tapered end of an adjusting screw —25— which is mounted 85 in a bracket or bearing —26— on the front edge of the wind chest —1—, the purpose of which is to tighten the belt when necessary by simply adjusting the screw so as to engage in the V-shaped groove —24—; that is, this adjusting screw is located some 90 distance above the co-axial pivots, as —27—, which support the wind chest —1— so that when engaged in the adjacent groove —24—, it will hold the wind chest against undue 95 rocking movement toward the motor, while the belt serves to hold the wind chest against rocking movement in the opposite direction or away from the motor, except as adjusted by the screw —26— in tightening the belt.

Each bellows —2— is connected by ports —28— with the interior of the wind chest —1—, while its movable side is adapted to communicate with the atmosphere through ports —29—, the ports —28— being provided with check valves —30— to permit the passage of air from the wind chest to the bellows and prevent its passage in a reverse direction, and are preferably arranged against the inner wall of the fixed side of the bellows so as to open into such bellows.

The ports —29— are also provided with check valves —31— to permit the escape of air from the corresponding bellows to the atmosphere as such bellows is collapsed and to prevent reentrance of atmospheric air when the bellows is distended, said valves —31— being located, in this instance, on the exterior of the movable side.

It is now clear that during the operation of the several bellows by the motor, the air is caused to flow more or less rapidly through the wind chest and ports, which under ordinary conditions produces more or less objectionable whistling noise, and in order to overcome this the opposite ends of the ports —28— and also the outer ends of ports —29— are covered by layers —32— of felt or equivalent air-pervious material adhe- 130

sively or otherwise secured to the adjacent walls of the wind-chest and bellows and constituting mufflers for dissipating the force of the air in transit through the ports, and thereby reducing to a minimum the noise incidental thereto.

In order that the air may have a free circulation through the wind chest, the felt layers —32— across the adjacent or inner ends of the ports —28— are held in spaced relation by a parting plate —33— of wood or equivalent material having a series of parallel lengthwise grooves —34— in opposite faces thereof so that the intervening ribs will hold the felt against entering the grooves, thereby maintaining a relatively large number of vertical air passages through which the air in the wind chest may freely circulate.

It will be noted that the resilient supporting pad —13— for the motor not only serves to prevent the transmission of vibrations from the motor to the instrument case, but also to the remaining parts of the wind-inducing device, such as the wind chest —1— and bellows —2—, and furthermore relieves the belt from excessive strains by reason of the fact that it is free to yield under varying loads applied to the pulling side of such belt.

From the foregoing description, it will be seen that the motor or the wind chest, together with its pumping bellows, may be easily and quickly removed independently of each other by simply removing the front screw of the bar —18— and the front bracket —20— without disturbing the rear

screw —18— or rear bracket —21—, thus permitting the motor and wind chest to be reinstalled after removal with the assurance that they will be in proper relative position.

A slight tightening of the belt may be effected by the tightening of the screws —19— by which the motor will be drawn down on its resilient supporting pad, but the major tightening of the belt may be effected by tightening the adjusting screw —25—.

What I claim is:

1. In a wind-inducing device for self-playing musical instruments, the combination of a wind chest and a pumping bellows communicating therewith through suitable ports, an air-pervious covering for said ports within the wind chest, and a grooved supporting plate for the covering having its grooves adjacent thereto to allow the air to circulate therethrough.

2. In a wind-inducing device for self-playing musical instruments, the combination of a wind chest, pumping bellows secured to opposite faces of the wind chest and communicating therewith through suitable ports, air-pervious coverings for said ports within the wind chest, and a rigid plate interposed between said coverings and provided with grooves adjacent the coverings for the circulation of air therethrough.

In witness whereof I have hereunto set my hand this 11th day of February, 1916.

LEWIS B. DOMAN.
